UNITED STATES PATENT OFFICE.

ENOCH W. RYDER, OF DECATUR, MICHIGAN.

ORCHARD-LADDER.

1,258,048.

Specification of Letters Patent.

Patented Mar. 5, 1918.

Application filed April 28, 1916. Serial No. 94,281.

To all whom it may concern:

Be it known that I, ENOCH W. RYDER, a citizen of the United States of America, residing at Decatur, in the county of Van

5 Buren and State of Michigan, have invented certain new and useful Improvements in Orchard-Ladders; and I do hereby declare the following to be a full, clear, and exact description of the invention, such as will 10 enable others skilled in the art to which it appertains to make and use the same.

This invention relates to an orchard ladder of the type shown in my previous Patent No. 1,119,883, granted December 8, 1914.

15 It is the object and purpose of the present invention to provide a device of this character with many new and useful improvements and novel features of construction and operation as hereafter described and 20 particularly pointed out in the claims, reference being had to the accompanying drawings, in which:

Figure 1 is a perspective view of the ladder.

25 Fig. 2 is a side elevation thereof; and

Fig. 3 is a side elevation, parts being shown in section of the mechanism for adjusting the main ladder element to various angular positions.

30 Like reference characters refer to like parts throughout the several views of the drawings.

In the construction shown a frame is provided including spaced apart horizontal side 35 beams 1 connected by front and rear cross beams 2 and 3, the frame being completed by an intermediate longitudinal beam 4 interposed between said cross beams. Posts

5 are provided at the rear ends of each beam 40 1 and extend downwardly being securely attached to said beams and braced by angle braces 6 so as to make a rigid construction. A flat metal bracing member is attached at substantially its middle point to the middle

45 of the transverse beam 2 as indicated at 7 extending thence forwardly and outwardly in both directions forming the bracing arms 8 which lead to the front ends of the beams 1 and are turned across said ends to form

50 sections 9 being then turned back alongside and spaced from the beams as shown at 10 and terminating in inwardly extending sections 11 lying along said beams and rigidly secured thereto. Wheels 12 are positioned

55 between the sections 10 and each beam 1 and are suitably mounted on axles carried by

and between said sections 10 and the beams as shown, there being formed in this manner a truck to support the ladder construction hereafter described.

Extending upwardly from the rear cross beam 3 are a pair of spaced apart uprights 13 connected together by a cross member 14 a short distance below their upper ends. A ladder consisting of side members 15 and 60 rungs 16 is located at the upper ends of the uprights and adjacent the middle of each of the side members 15 and on the underside thereof a block 17 is secured which passes between a member 18 and the upper end 65 of an upright 13, bolts passing through said uprights and members 18 for pivotally connecting the ladder to the uprights. The ladder is braced and strengthened by posts 19 extending upwardly at right angles in 70 each side 15 and by brace rods 20, the ends of which are secured to angle clips 21 near the ends of the ladder sides 15, said rods passing through the posts 19 so that 75 in effect a truss is formed capable of withstanding heavy loads.

Rearwardly extending handles 22 are attached at their forward ends adjacent the lower ends of the uprights 13. Brace members 23 lead from these handle members to 85 the posts 5 and similarly brace members 24 lead from near the middle of each handle to the uprights 13 at a point substantially midway between their upper and lower ends. These handle members permit the 90 raising of the rear part of the truck and movement of the entire truck forward on the wheels when a change of position is desired.

The uprights 13 are located a distance inwardly from the side beams 1. A ladder comprised of side members 25 and 26, a top piece 27 and a plurality of horizontal rungs 28 is secured at each side of the truck, the lower ends of the side members being rigidly 95 attached to the beams 1 while the tops 27 lie against the uprights 13, the ladder being secured to these uprights in any suitable manner. A horizontal bar 29 is fastened to the sides 26 of the two ladders, its ends 100 extending a distance to each side of said members and bars 30 secured at their upper ends adjacent the ends of this rod 19 extend downwardly and forwardly to the beams 1 and are rigidly secured thereto 110 near their forward ends. Each bar on its underside is provided with a plurality of

notches 31. A platform comprised of a plurality of boards 32 connected by cleats 33 is mounted upon the bar 30, spaced apart straps 34 being attached at either side of 5 each cleat and passing to either side of the bar 30 and having a pivotal connection to a block 35 slidably mounted on the underside of each bar 30. A projection 36 is formed on the upper side of each block 35 10 which is adapted to seat in a notch 31, it being apparent that the platform can be readily adjusted to a plurality of positions with respect to the supporting bars 30.

A rod 37 is pivotally connected at its rear 15 end to the main ladder element comprised of sides 15 and rungs 16, this rod extending forwardly between the uprights 13 and having a pivotal connection at its forward end with bars 38, these bars being spaced apart 20 a short distance and extending downwardly to a point below the cross beam 3 and at their lower ends pivotally connecting to the rear end of a bar 39 located directly below the beam 4 and at its forward end connected 25 to said beam by the links 40 as shown. Links 41 are connected to the bar 39 a distance back of links 40 extending upwardly to either side of the beam 4 and having a pivotal connection at their upper ends to the front end of a bar 42 which is mounted 30 above the beam 4 and supported thereon by links 43 pivotally connected to said beam at its rear end and to the bar 42 at substantially its middle point. The rear part of 35 bar 42 is slotted for the passage of bars 38. From the rear end of the bar 42 rods 44 extend upwardly and have permanent connection with the cross member 14 heretofore described. A bar 45 having a plurality of 40 openings 46 therein is pivotally connected at its upper end to the rod 37 at a point substantially midway between the ends thereof and extends downwardly between the bars 38 which have each a plurality of openings 45 47, it being apparent that the bar 45 may be moved to various positions bringing various openings 46 thereon in coincidence with openings 47 in the bars 48 so that a pin may be inserted therethrough to retain the parts 50 in fixed relation. With this link and lever construction when weight is applied to the upper end of the ladder (referring to Fig. 2) the front end of lever 42 bears against the intermediate beam 4 while with the 55 weight applied to the opposite end of the ladder, the strain is transmitted to the rods 44 causing a tension therein. In this manner the strains made by application of weight to either end of the ladder are best 60 taken care of without necessitating the use of heavy bars to take compression with the extra weight thereof.

A ladder of the construction described is portable and may be readily moved over the ground to any desired position with respect

to a fruit tree. For the lower branches the platform supported by the bars 30 may be used and it may be adjusted to a plurality of positions so that practically all the lower branches of a tree may be reached. For 70 branches somewhat higher the side ladders may be used and for the remainder of the tree the main ladder pivotally mounted at the upper ends of uprights 13 may be used, this ladder being adjustable to any desired 75 position and being readily reached from the top pieces 27 of each of the side ladders. The link and bar connection by means of which the main ladder is adjusted provides a construction in which any strain transmitted 80 from the main ladder is finally received by the rods 44 and the cross member 14, the construction being one that is of especial strength and durability and one in which the strains are transmitted in direct 85 lines without the creation of eccentric strains which would be much harder to take care of and for which a durable construction would be much harder to be made.

I claim:

1. In an orchard ladder, a truck, upright spaced apart standards on the truck, a ladder pivotally mounted between its ends to and between the upper ends of said standards, means for adjusting and holding the 95 ladder in a plurality of different angular positions, ladders secured at their lower ends to the truck and at their upper ends to said standards, a horizontal rod carried by said last mentioned ladders adjacent the upper ends, spaced apart bars connected to said rod and extending downwardly and forwardly to the front end of the truck, and a platform in front of said bars adjustably mounted thereon, substantially as described. 105

2. In an orchard ladder, a truck including spaced apart side beams connected by front and rear cross beams, an intermediate beam attached to and between the cross beams, a pair of links depending from said intermediate beam near its front end, a bar lying below said intermediate beam and pivotally connected at its front end to said links, a second pair of links extending upwardly from adjacent the rear end of said beam, a second 115 bar pivotally connected at substantially its middle point to said links, a third pair of links connected to the front end of the second bar and to the first bar a distance back of the front end thereof, an upright support 120 on the truck, rods secured to the rear end of the second bar and extending upwardly and attached to the upright support adjacent its upper end, a ladder pivotally mounted between its ends to the upper end of said support, a rod pivotally connected adjacent the rear end of said ladder, and extending downwardly and forwardly, bars provided with a plurality of openings therethrough pivotally connected at their upper ends to 130

the front end of said rod and at their lower ends to said first bar and a bar pivotally connected at its upper end to the rod between its ends and extending between the 5 two bars provided with openings, said last mentioned bar also having a plurality of openings therein adapted to be placed in conjunction with said first mentioned openings in said bars to receive a pin there-through, substantially as described.

3. In an orchard ladder, a truck, an upright on the truck, a ladder pivotally mounted between its ends at the upper end of the truck, a rod pivotally connected at one end 15 adjacent the rear end of the ladder and extending downwardly and forwardly, a bar pivotally connected to the forward end of the rod, a second bar pivotally connected to

the lower end of the first bar extending under the truck and having pivotal connection at its front end thereto, a third bar located above the truck and pivotally mounted at its middle point thereon, links connecting the front end of the third bar with said second bar, rods connected to the rear 20 end of the third bar and extending upwardly and fastened to the support, a fourth bar pivotally connected at its upper end to the first named rod at a point between the ends thereof and extending downwardly and 25 forwardly to the first named bar, and means to connect said fourth and first bars together at a plurality of different positions, substantially as described.

In testimony whereof I affix my signature. 30
ENOCH W. RYDER.
